UNITED STATES PATENT OFFICE.

FERDINAND MORA CANDA, OF NEW YORK, N. Y.

BALL-ROLLING APPARATUS.

1,399,687.

Specification of Letters Patent.

Patented Dec. 6, 1921.

Application filed December 1, 1919. Serial No. 341,785.

To all whom it may concern:

Be it known that I, FERDINAND MORA CANDA, a citizen of the United States of America, and resident of the borough of 5 Manhattan, city, county, and State of New York, have invented a Ball-Rolling Apparatus, of which the following is a specification.

My invention relates to ball rolling apparatus and constitutes an improvement upon, 10 and an addition to, the invention of my prior application for the same purpose, Serial No. 332,284, filed October 21, 1919. The apparatus of that application comprises 15 acting grooved ball-forming rolls, together with means for moving one of said rolls toward and from the other, and together with one or more so-called locators for determining the position between said rolls and the 20 material to be acted upon. It is desirable that these locators shall always be directly above or below, as the case may be, the balls being formed. My present invention comprises means whereby this is accomplished. 25 In case one only of the main rolls is shifted, according to my present invention, the said locator or locators is or are shifted correspondingly; but alternatively, I may keep the locator or locators stationary, and shift 30 both ball-forming rolls, equally, but in opposite directions.

The object of my invention is to maintain the locator or locators of the said former machine directly above or below, as the case 35 may be, the forming balls during the operation of rolling the same.

I will now proceed to describe my invention with reference to the accompanying drawings and will then point out the novel 40 features in claims.

In said drawings:

Figure 1 shows a side elevation and partial vertical section, and

Fig. 2 a top view, with a portion broken 45 away, of one form of apparatus embodying my invention;

Fig. 3 shows a side elevation and partial vertical section, and

Fig. 4 a top view, with a part broken 50 away, of a second form of machine embodying my invention.

Fig. 5 is a side elevation, and

Fig. 6 a top view of a further form of machine embodying my invention.

55 Referring first to Figs. 1 and 2: 1 design-

nates a suitable frame for the machine, and 2 and 3 indicate grooved coacting ball-forming rolls, mounted in suitable bearings 4 and 5, bearings 5 being mounted to slide in ways in frame 1, and suitable means, as for example, ram devices 6, controlled by a valve 7, being provided for so sliding said bearings 5 and the roll 3. 8 and 9 designate what I term "locators" for determining the position between rolls 2 and 3, of the material to be rolled into balls, and for preventing the escape of the balls until such escape is desired. These locators may be transverse frames carrying idler rollers 10. For adjustment, ram devices 11 and 12 may be provided for these locators. As so far described the construction is that of my said prior application. 14 designates the material to be rolled into balls.

In the construction shown in Figs. 1 and 2, for maintaining the locators 8 and 9 directly above or beneath, respectively, the forming balls 14, these locators are mounted to slide in ways 15 in the frame, and are connected by links 16 to levers 17 pivoted at 18 to the frame and pivoted at 19 to the bearings 5. Obviously, as the ram devices 6 move the roll 3 and its bearings 5 in and out, the locators 8 and 9 will be moved in the same sense as the roll, but through one-half 80 the distance, thereby keeping these locators directly above or below, respectively, the balls 14 being formed.

In the alternative arrangement shown in Figs. 3 and 4, the locators 8 and 9 are stationary, and the rolls 2 and 3 are both moved in and out, their bearings, here designated as 4^a and 5^a respectively being formed to constitute nuts for screws 20 and 21, of opposite pitch for the two rolls respectively, 95 these screws being arranged to be turned by a shaft 22 and suitable bevel gearing 23. It will be obvious that by means of the shaft 22 of the bevel gearing both rolls 2 and 3 may be moved together or may be moved apart, 100 but in each case the rolls will move equal distances, and therefore the locators will remain central above and below the forming balls.

Obviously various means may be employed for moving the rolls 2 and 3 in and out; and I do not limit myself to any particular means for this purpose. One further means for the purpose is shown in Figs. 5 and 6 comprising toggle levers 24 pivoted 110

to the bearings for rolls 2 and 3, and to each other, and arranged to be actuated by ram devices 25.

What I claim is:

- 5 1. In a ball rolling apparatus, the combination of coacting grooved ball-forming rolls, locating means for determining the position between said rolls of material to be acted upon, and means for separating said ball-forming rolls and bringing them together, whereby said locating means is maintained in central position with respect to the material to be acted upon.
- 10 2. In a ball rolling apparatus, the combination of coacting grooved ball-forming rolls, means for moving one of said rolls toward and from the other, locating means for determining the position between said rolls of material to be acted upon, and means for moving said locating means with the move-

able roll but through half the distance of movement of said movable roll.

- 15 3. In a ball rolling apparatus, the combination of coacting grooved ball-forming rolls, one of which is mounted to be moved toward and from the other, means for so moving said roll, locating means for determining the position between said rolls of material to be acted upon, and levers pivoted at one end to fixed points and connected at the other end to said rolls and means connecting said levers at mid-points to the said locating means.

In testimony whereof I have signed this specification in the presence of two sub- 35 scribing witnesses.

FERDINAND MORA CANDA.
